DESIGN FOR A STAND FOR SUPPORTING TESTING EQUIPMENT

William K. Anderson, Dearborn, Mich., assignor
to Westinghouse Electric & Manufacturing
Company, a corporation of Pennsylvania

Application November 13, 1934, Serial No. 53,996

Term of patent 7 years

To all whom it may concern:

Be it known that I, William K. Anderson, a citizen of the United States, residing at Dearborn, in the county of Wayne and State of Michigan, have invented a new, original, and ornamental Design for a Stand for Supporting Testing Equipment, of which the following is a specification, reference being had to the accompanying drawing, constituting a part hereof.

Figure 1 is a view, in perspective, of the front of a stand for supporting automobile testing equipment designed in accordance with the present invention;

Fig. 2 is a view, in perspective, of the rear of the cabinet shown in Fig. 1; and

Fig. 3 is an enlarged view, in section taken on the line III—III of Fig. 1.

I claim:

The ornamental design for a stand for supporting testing equipment, substantially as shown.

In testimony whereof, I have hereunto subscribed my name this 8th day of November, 1934.

WILLIAM K. ANDERSON.
